US00D548120S

(12) **United States Design Patent** (10) Patent No.: **US D548,120 S**
(45) Date of Patent: ** Aug. 7, 2007

(54) **DIGITAL GAUGE**

(75) Inventors: **Yuji Nagai**, Saitama (JP); **Hideo Maejima**, Saitama (JP); **Osamu Ochiai**, Saitama (JP)

(73) Assignee: **Sony Corporation**, Tokyo (JP)

(**) Term: **14 Years**

(21) Appl. No.: **29/239,315**

(22) Filed: **Sep. 29, 2005**

(30) **Foreign Application Priority Data**

Apr. 1, 2005 (JP) D2005-009913

(51) LOC (8) Cl. **10-04**

(52) U.S. Cl. **D10/85**; D10/96; D10/99

(58) **Field of Classification Search** D10/85, D10/96, 99; 73/37, 700, 735, 736, 714, 756, 73/729.1; 186/271, 273; 280/734, 737, 280/738; 340/626, 627

See application file for complete search history.
